APPARATUS FOR DEVELOPING FILMS

Jacob A. Saffir, Rockford, Ill.

Application December 26, 1931
Serial No. 583,213

3 Claims. (Cl. 95—93)

This invention relates to a method of and means for developing photographic films, especially such films as are of a comparatively small size, such as X-ray films or the like.

5 In the development of photographic films it is necessary to subject the films to successive chemical actions and to thereafter wash the same with water. It is desirable that the film be agitated during the time it is being developed, 10 in order to procure an even development of the film. It is an object of this invention to provide an apparatus wherein the film can be placed for development purposes and which apparatus may receive the various tanks containing the various 15 reagents necessary for developing the film, all without manual handling of the partly developed film. The apparatus is provided with a tank receiving portion wherein there is removably placed a tank containing the reagents necessary in the 20 initial development of the film. The film is held in a substantially C-shaped clip which is then lowered into the solution and suitably agitated therein. After it has been in the developer solution its prerequisite period of time the parts holding 25 the film are swung out of the tank and the tank is replaced by another containing the fixing solution. The film holding portion of the apparatus is then swung into this second tank where the fixing takes place. This procedure is 30 repeated until the film has been fully developed and washed. The apparatus is adapted to impart continuous or intermittent motion to the film thereby keeping the film constantly moving through the solution and maintaining the solution 35 itself in constant motion, or keeping the film and the solution in only intermittent motion, as desired. The film may be given any desired type of motion, for instance, an up and down motion, a side to side motion, an end to end motion, 40 a swirling or rotating motion, or any combination of the same.

The attainment of the above and further objects of the present invention will be apparent 45 from the following specification taken in conjunction with the accompanying drawing forming a part thereof.

In the drawing:

Figure 1 is a side view, in partial section, illustrating one embodiment of my invention;

Figure 2 is a fragmentary end view showing a portion of the apparatus;

Figures 3, 4 and 5 are fragmentary diagrammatic views illustrating modified forms of my 55 invention; and

Figure 6 is an end view of the apparatus corresponding to that shown in Figures 4 or 5.

Reference may now be had more particularly to the form of my invention illustrated in Figure 1. The developing apparatus comprises a base 1 to which is secured an upwardly extending standard 2 having a horizontal member 3 hinged thereto as by means of a hinge indicated at 4. The horizontal member has a U-shaped bracket 5 secured to its lower side and depending towards the base 1. A shaft 6 is rotatably mounted between the arms of the U-shaped bracket and carries an L-shaped arm 7. A pair of substantially C-shaped spring clips are fastened to the L-shaped arm in any desired manner, as by welding or the like. The arm 7 has a bent back portion through which the shaft 6 passes and which carries a stud 10 for removably keying the arm to the shaft.

The shaft 6 has a rotatable driving wheel secured thereto at 11 and adapted to rotate the shaft. A chain or the like, indicated at 12, passes over the driving wheel and through a suitable opening in the member 13 and around a drive wheel 14. The drive wheel 14 is keyed to a drive shaft 16 that is carried by the member 3 in any suitable manner, as by means of a pair of brackets 17—17. The shaft 16 is adapted to be turned by means of a handle 20 to thereby turn the shaft 6 and the clips 8.

In order to use the apparatus shown in Figure 1 the member 3 is swung about its hinge in a clockwise direction to elevate the mechanism carried by the bracket 5. One or more films are then placed in the clips 8—8. I have indicated such films at 25—26. The lower edge of the film may engage the extension 27, as in the case of the film 25, or it may engage the curved body portion 28, as in the case of film 26. A tank, such as indicated at 30, containing the developing solution is placed upon the base 1 and the horizontal member is then lowered to the position indicated in Figure 1. This brings the films into the developing solution. The handle 20 is then turned to rotate the shaft 6 and thereby move the films within the solution. The handle is preferably turned rather slowly and, in order to further reduce the speed of rotation of the shaft 6, I use a small drive wheel on the shaft 16 and a larger drive wheel on the shaft 6. This, however, is optional. After the film has been in the developer solution the required length of time the member 3 is swung about its hinge to bring the apparatus carried thereby out of the tank 30. The tank may then be removed and replaced

110

by a different tank containing the fixing solution. The member 3 is then again lowered to the position shown in Figure 1 and the handle 20 is again turned to turn the films within the fixing solution. This procedure may be repeated for the subsequent washing of the film.

While I have herein shown a chain 12 for transmitting the motion to the shaft 6 it is of course to be understood that any other well known motion transmitting means or gear may be used. Also the shaft 16 may be replaced by a small electric motor and suitable speed reducing gearing, if desired.

In Figure 3, I show an arrangement wherein the clips 8-8 are secured to a belt or other conveyor 40 which moves on two pulleys indicated at 41 and 42. One of these pulleys, preferably the pulley 41 comprises the driving pulley and it is supported in any desired manner, as from the horizontal member 3 of Figure 1. In this case, it is to be noted that as each clip passes over the upper pulley 41 it passes out of the developing solution within the tank 30'. Thus each film is alternately dipped into and out of the developing solution.

In Figure 4, I show an arrangement wherein a shaft 50, which corresponds to the shaft 6 of Figure 1, extends vertically instead of horizontally. This shaft may be supported from an apparatus such as is shown in Figure 1 in any desired manner and may be rotated in any well known desired manner. For this purpose I have shown a sprocket 51 secured to the shaft 50. A shaft 50' is detachably secured to the shaft 50 as by means of a collar 52. The clips 8 are secured to the shaft 50' and extend radially outwardly therefrom. In Figure 4, I have shown three clips secured to one side of the shaft and three more clips secured to the other side of the shaft. The two lower sets of clips are shown as holding X-ray films wrapped in their original package and adapted to be developed within the package in the manner disclosed in my copending application Serial No. 570,841, filed October 24, 1931. It is, of course, to be understood that an ordinary X-ray film may be placed in those clips in lieu of the films there shown. As the shaft 50' is rotated the films are moved through the solution within the tank. The shaft 50' is adapted to be elevated from the developing tank in the manner illustrated in Figure 1.

In Figure 5, I have shown a fragmentary portion of a modification of the structure shown in Figure 1. This structure differs from that of Figure 1 in that the shaft 6' of Figure 5 is in alignment with the shaft 6, being removably secured thereto in any desired manner, as by means of a collar 55 which receives the ends of the shafts 6-6' and is secured to both of them by radially extending studs. The shaft 6' carries the film clips. The clips 8-8 are secured directly to this shaft rather than through the arm 7 of Figure 1. I have herein shown five clips secured to this shaft in spaced relation. It is to be noted that the clips are arranged to hold the films at an angle to the axis of the shaft, the angle is such that all of the films constitute portions of the surface of a screw propeller for propelling the liquid within the developing tank in a generally forward direction. By this arrangement the liquid within the enclosing tank is effectively circulated and any foreign matter

that may be present is washed from the surface of the film due to the inherent washing action of the liquid moving along the surface of the film.

If desired, the clips 8 may be secured to the shaft in such position as to radiate therefrom in substantially Y formation as seen in end view. This is illustrated in Figure 6. This arrangement is applicable to the forms of my invention illustrated in Figures 4 and 5. If desired, the film holding clips in Figure 4 may be mounted 90 degrees apart, rather than 120 degrees apart as shown in Figure 6, or 180 degrees apart as shown in Figure 4, or they may be spaced apart any other desired angular distance.

From the description thus far given it is apparent that I have provided a simple machine for developing a large number of films whether the films are in their original wrapping or are unwrapped films. It is of course understood that if the present device is used for developing unwrapped films it must be used in a dark room or the like. My device is simple in its construction and operation and requires a negligible amount of attention or handling of the films.

I claim:

1. Film developing apparatus comprising an upright standard, a horizontal member hinged to said standard, a rotatable shaft carried by the horizontal member and depending therefrom, film receiving spring clips carried by the shaft and movable therewith, means on the horizontal member for rotating said shaft to rotate said clips, a liquid receiving tank beneath the horizontal member and into which the shaft extends, said horizontal member being hinged about a horizontal pivot to permit vertical swinging of the horizontal member to move the shaft out of the tank.

2. Film developing apparatus comprising a base, an upright standard thereon, a horizontal member carried by the standard above the base, a removable tank supported on the base beneath the horizontal member, a bracket secured to the under side of the member and depending into the tank, a rotatable shaft mounted on the lower end of the bracket, a film receiving clip carried by the shaft and rotatable thereby in the tank, a driving wheel keyed to the shaft for driving the same, a driving shaft carried by the horizontal member on the upper side thereof, and a driving connection between the last mentioned shaft and the driving wheel.

3. Film developing apparatus comprising a base, an upright standard thereon, a horizontal member carried by the standard above the base, a removable tank supported on the base beneath the horizontal member, a bracket secured to the under side of the member and depending into the tank, a rotatable shaft mounted on the lower end of the bracket, a film receiving clip carried by the shaft and rotatable thereby in the tank, a driving wheel keyed to the shaft for driving the same, a driving shaft carried by the horizontal member on the upper side thereof, and a driving connection between the last mentioned shaft and the driving wheel, said horizontal member with the parts carried thereby being swingable as a unit with respect to the base to permit removal and replacement of the tank.

JACOB A. SAFFIR.
